AUTOMATIC VENDING MACHINE
ATTACHMENT

Richard R. Dunn, Windsor Locks, Conn.

Application December 20, 1941, Serial No. 423,714

9 Claims. (Cl. 194—1)

This invention relates to improvements in automatic vending machines.

Automatic vending machines in general have the disadvantage that dishonest persons are able to insert slugs, improper coins or other objects therein to effect operation of the machine, resulting in considerable losses in revenue, and sometimes damaging or jamming the machines. Since automatic vending machines are usually inspected by an attendant only at relatively infrequent intervals, detection of persons deliberately inserting improper objects is seldom possible.

Numerous devices have been proposed and some installed on automatic vending machines to prevent this improper operation, but this involved relatively complicated and expensive mechanisms.

It is an object of the present invention to provide simple and efficient means whereby the use of automatic vending machines is restricted to a number of selected and trusted persons, whereby the need for providing complicated slug-detecting protective devices is obviated.

To accomplish this object, means is provided for normally closing the coin-receiving aperture of an automatic vending machine, operable by means of a lock mechanism or similar device to open the aperture temporarily. The lock, if desired, may be operated by a combination known only to those authorized to use the machine, but preferably it is operated by means of keys which are distributed among the selected persons.

Thus, according to the present invention, where the automatic vending machine is to be used only by a cooperative, club, or other group or organization, only those persons provided with the combination or key may use the machine, and the necessity for complicated mechanisms to prevent operation of, or damage to, the machine from the insertion of slugs is substantially obviated.

Preferably, the lock is so arranged as to prevent removal of the key unless the coin-receiving aperture is first closed, so that the possibility of one of the users inadvertently leaving the slot open is rendered very unlikely. The lock-operated mechanism of the invention, for opening and closing the coin-receiving aperture, is characterized by utmost simplicity and effectiveness and may be economically manufactured largely of sheet metal stampings.

Sometimes, an authorized user of the machine may inadvertently attempt to insert a coin of incorrect denomination. If the coin is too large, the limited size of the aperture readily prevents

insertion, but if smaller than the correct coin, it readily enters the aperture.

It is a further object of the present invention to provide means for conveying coins of the correct denomination to the automatic vending mechanism by gravity, while smaller coins are automatically returned also by gravity to a coin-return receptacle on the exterior of the machine.

The latter object is accomplished by providing a coin-return chute of simple and effective design for sorting coins inserted into the aperture.

The device of the present invention is especially applicable for use in automatic vending mechanisms for gasoline pumps, beverage or other liquid-dispensing machines, as well as machines for dispensing packages or objects, where use of the machine is to be limited to a selected group of persons.

The invention is illustrated by the embodiment hereinafter described with reference to the accompanying drawing, in which:

Fig. 1 is a front view of a panel or fragment of the face of an automatic vending machine, including a coin-receiving slot and a coin-return aperture and receptacle.

Fig. 2 is a side view of said panel, showing the slot closing mechanism and coin-sorting chute of the invention.

Fig. 3 is a rear view of the panel, including the mechanism of Fig. 2 and showing the coin chute in cross-section along the line 3—3 in Fig. 2.

Fig. 4 is a plan view of the said panel, mechanism, and coin chute.

As illustrated in the drawing, the panel 10 comprises a slot 11 of suitable dimensions to just permit insertion of coins of the correct denomination but too small to permit the insertion of larger coins. Below the said slot, a coin-return aperture 12 is formed with a tray 13 for catching coins falling through said aperture.

A slot-closing mechanism 14 is secured to the rear of the panel 10, comprising a plate 15 secured to the panel, as for instance by rivets 16a, having a slot or aperture therein coinciding with the aperture 11 in the panel. A guide plate 16 is secured to the rear surface of the plate 15, as for instance by means of screws 17 and is provided with a similar aperture registering with the slot 11. Opposite edges of the plate 16 are flanged over to provide a pair of parallel guides 18, which carry a slot-closing member 19 comprising a plate, the opposite edges of which are engaged by the said guides. The slot-closing member 19 is provided with an aperture 20 adapted, when said member is in a given position, to

register with the slot 11 in the panel 10 and the corresponding apertures or slots in the plates 15 and 18. A fixed tab or lug 21, lanced outwardly from one end of the plate 18, is connected by means of a tension spring 22 to a corresponding tab or lug 23 similarly lanced from the corresponding end of the slot-closing member 19. The said spring normally urges the slot-closing member 19 to a position in which the slot 20 therein is out of register with the slot 11 of the panel, that is, to the right in Fig. 3, thereby preventing insertion of coins through the said slot. Screws 17 may, if desired, project sufficiently from plate 18 to engage the right-hand end of the slot-closing member 19, so that they serve as stop means limiting slot-closing movement of said member under the influence of spring 22.

The operating mechanism, according to the invention, for moving the slot-closing member 19 so as to bring the slot 20 into registry with the slot 11, that is to the left in Fig. 3 and thereby permit the insertion of a coin into the machine, comprises a lock 24 of the conventional Yale type. The lock is operable by a key, inserted in the keyhole 24a from the front of panel 10, and comprises a barrel 25 rotatable about its axis by means of the key when the latter is inserted therein. In locks of this type, the key is adapted to coalign a number of tumblers normally preventing rotation of the barrel, so as to permit rotation of the barrel. Furthermore, in conventional locks of this type, the key can only be inserted when the barrel is in a predetermined angular position, and the barrel must be returned to this position in order to remove the key.

The inner end of the barrel 25 carries a radial finger 26 secured thereto having a cam surface 27 on its end. A bracket 28, secured to the rear surface of plate 18 by means of a screw 29, comprises a pair of lugs 30 and 31 lanced therefrom and extending into the path of the finger 26 so as to limit its movement to an angle less than a full revolution, for instance an angle of about 90° as shown. When the barrel 25 of the lock 24 is positioned for insertion or removal of the key, the finger 26 is vertically positioned engaging lug 30 as shown in Fig. 3.

At one side, adjacent slot-closing member 19, the bracket 28 has a tab 32 bent into a horizontal plane for pivotally supporting an operating lever 33 for the slot-closing member 19. One end of the said lever is bifurcated as indicated at 34, the prongs thereof engaging a projection 35, included between them, said projection being formed by means of a crimped piece of sheet metal 36, secured as for instance by rivets, spot welding or screws, to the slot-closing member 19.

The opposite end of the operating lever 33 extends into the path of the radial finger 26 carried by the lock barrel 25. Cam surface 27 is adapted, when the said finger is rotated by the barrel 25 through an angle of 90° from its initial position to the opposite limit of its motion in which it engages lug 31, as illustrated by dotted lines in Fig. 3, to engage the projecting end of the operating lever 33 and to rock the lever about its pivot, moving the engaged end of the lever to the right. The resulting movement in the opposite direction of the bifurcated end 34 of the lever 33 moves the projection 35, and hence the slot-closing member 19, to the left against the tension of the spring 22.

The cam 27 and lever 33 are so constructed that the said movement of the radial finger 26 to the limit of its motion brings the slot 20 in

the slot-closing member 19 into registry with the slot 11 in panel 10. Thus, upon insertion of a key in the lock 24 and turning it through an angle of 90°, the slot-closing member 19, normally urged by spring 22 to slot-closing position, is moved in its guides 18 to slot-registering position so that a coin may be inserted through slots 11 and 20 into the vending machine. Since the slot-opening operation of the lock is limited to less than a full revolution of its barrel, the key cannot be removed from the lock as long as the slot is open. Upon return of the lock barrel to its initial position, lever 33 is released; spring 22 returns the slot-closing member 19 to its initial position, and the key is released for removal by conventional means in the lock 24.

A coin chute 37 is secured to the plate 15 or rear surface of panel 10 as for instance by screws 38. This chute comprises a substantially vertical portion 39 through which coins drop by gravity when inserted through the slots 11 and 20 during mutual registration thereof. The lower end of the vertical portion 39 of chute 37 communicates at a relatively abrupt elbow with an inclined chute portion 40 forming an obtuse angle with the vertical portion 39, and having a sufficiently steep incline to permit coins to slide downward therein by gravity. The lower end of the inclined portion 40 of the chute 37 communicates with coin-operated delivery mechanism 41, and is adapted to deposit coins therein, either for mechanically or electrically actuating or priming said mechanism for operation, after which the coin is deposited in a collecting compartment. The automatic delivery mechanism 41 may be of any conventional design.

The inclined portion 40 of the chute 37 is constructed of just sufficient breadth to accommodate coins of the desired denomination, as for instance fifty cent pieces. An elongate aperture or slot 42 is formed in the lower surface of the inclined portion 40 of chute 37 substantially centrally located in said surface so as to provide a pair of flanges 43 on opposite sides of the aperture of sufficient breadth to support coins of the correct denomination thereon as long as such coins remain flat against the lower surface of the chute. The breadth of aperture 42 is sufficient however to permit coins of the next smaller denomination (e. g. quarters) to fall through it.

Because of the narrowness of flanges 43, it is possible that coins of the correct denomination might bounce in such a manner that they would encounter the aperture 42 without lying flat against flanges 43 and would consequently fall diagonally through the aperture and fail to reach the delivery mechanism 41.

According to the present invention, means is provided to prevent this from happening. This means comprises a weakly resilient tongue 44 having an offset 44a at its lower end secured, for instance by spot welding or soldering, to the upper surface of the inclined chute portion 40, at a point adjacent the lower end of aperture 42. The upper end of the tongue is bent upwardly as indicated at 45 adjacent the junction of the vertical and inclined portions 39 and 40 of the chute 37 so that a coin falling through chute 39 cannot enter the space above the tongue 44 in chute 40. The said tongue is normally yieldably positioned so that the flanged end 45 does not engage the upper surface of the chute 40. Preferably, it is normally positioned adjacent to the lower surface of said chute and may even touch the lower surface.

When a coin 46 reaches the angular junction or elbow of the two chute sections 39 and 40, it encounters the lower surface of flange 45 and is momentarily positioned as shown with one edge resting against the lower surface of chute 40 and the opposite edge resting against one side of chute 39. The weight or momentum of the coin causes the tongue 44 to yield resiliently upward to permit the coin to pass by, but insures that the coin emerges from the elbow, in such position that it lies flat against the lower surface of chute 40. Any tendency of the coin to bounce is largely eliminated at the elbow, and is further checked by the proximity of the tongue 44 to the lower surface of the inclined chute. Thus, if the coin is of the correct denomination, it slides down the said chute with its edges engaging both flanges 43 so that it cannot fall through the aperture 42.

However, if a smaller coin is inserted, the tongue 44 tends to urge the coin downward as it passes the elbow at the junction of the two chute portions, so that the edges thereof fail to engage one or the other of flanges 43 and the coin falls downward through the aperture 42 before it can reach the delivery mechanism 41 of the vending machine.

Beneath the aperture 42, a coin return chute 47 extends downwardly at an angle from chute portion 40 and is adapted to deposit the coin on an inclined surface 48 leading to the coin return aperture 42 at the front of the panel 10. Accordingly, when an improper coin falls through the aperture 42 into the chute 47, it slides onto the inclined surface 48 and thence outward through the aperture 42 into the coin-return tray 48 from which it may be recovered by the owner.

The automatic vending mechanism 41 may be arranged to operate or to permit operation of a mechanism for delivering predetermined amounts of gasoline, beverages, packages or other articles to a purchaser. As stated above, the device of the present invention substantially obviates the possibility of tampering with the machine by persons unauthorized to use it, thus substantially removing the problem of loss or damage by insertion of slugs. The fact that the key cannot be removed from the lock until the slot is closed substantially eliminates the possibility of leaving the machine open through carelessness of a user. The coin-return device provides a simple and efficient means for returning coins of incorrect denominations which may be inserted into the slot. The slot-closing mechanism is simple and effective and may be economically constructed largely from sheet metal stampings.

If keys are lost and fall into the hands of other persons, or if some of the authorized users prove to be dishonest and are detected, they may be readily prevented from further use of the machine by simply changing the lock and issuing new keys. While a combination lock, which usually has a number of tumblers normally preventing releasing operation thereof and movable to effect such release by an unobvious sequence of predetermined manipulations, could be substituted for the key-operated lock described above, the latter is preferred since combination locks ordinarily permit leaving the slot open by mistake.

Variations and modifications may be made within the scope of this invention and portions of the improvements may be used without others.

I claim:

1. In an automatic vending machine having a coin-receiving aperture in the exterior surface thereof, a member slidably movable across said aperture on the interior of the machine for opening and closing thereof; yieldable means normally urging said member to aperture-closing position; cam means for moving said member to aperture-opening position and for blocking said member in said position; and a lock mechanism operable only by a removable member for moving said cam means in aperture-opening direction, said lock being adapted to receive said removable member and to release said member for removal therefrom only while said slidable member is in aperture-closing position.
2. In an automatic vending machine, a coin-receiving aperture in the exterior surface thereof; a member slidably movable across said aperture on the interior of the machine for opening and closing said aperture; resilient means normally urging said member to slot-closing position; a pivoted rocker member for moving said slidable member to aperture-opening position; cam means adapted to engage and operate said rocker member for moving said slidable member to aperture-opening position and for blocking return movement of said member; and operating means for said cam comprising a concealed instrumentality requiring predetermined unobvious complementary manipulation for operation thereof.
3. In an automatic vending machine having a coin-receiving aperture in the exterior surface thereof; a plate adapted to cover said aperture; guide means on the interior of the machine slidably carrying said plate for movement to cover and uncover said aperture; resilient means normally urging said plate to aperture-covering position; a pivoted rocker member engaging said plate for movement thereof to aperture-uncovering position; rotatable cam means for temporarily moving said rocker member to slide said plate to aperture-opening position and blocking the same in open position; and rotatable operating means for said cam comprising a concealed instrumentality requiring predetermined unobvious complementary manipulation for operation thereof.
4. In an automatic vending machine having a coin-receiving aperture in the exterior surface thereof; a plate adapted to cover said aperture; guide means on the interior of the machine slidably carrying said plate for movement to cover and uncover said aperture; resilient means normally urging said plate to aperture covering position; a pivoted rocker member engaging said plate for movement thereof to aperture-uncovering position; rotatable cam means for moving said rocker member so as to move the plate slidably to aperture-uncovering position; and a lock mechanism requiring a removable member for operating said cam means, said lock being adapted to receive said removable member and to release said member for removal therefrom only while said plate is in aperture-covering position.
5. In an automatic vending machine having a coin-receiving aperture in the exterior surface thereof; a plate adapted to cover said aperture; guide means on the interior of the machine slidably carrying said plate for movement to cover and uncover said aperture; resilient means normally urging said plate to aperture-covering position; a pivoted rocker member engaging said plate for movement thereof to aperture-uncover-

ing position; rotatable cam means adapted to engage said rocker member for moving it so as to move said plate slidably to aperture-opening position; a lock having a rotatable barrel upon which said cam is mounted, requiring a removable member for operation thereof; and stop means limiting angular movement of said lock barrel and cam to less than a full revolution and in slide-blocking position, said lock being adapted to receive said removable member and to release said member for removal therefrom only while said cam is positioned to permit the plate to cover the aperture.

6. In an automatic vending machine having a coin-receiving aperture in the exterior surface thereof, a movable slide for opening and closing said aperture; yieldable means normally urging said slide to aperture-closing position; and manually operable means actuated by a removable member, said means being rotatably mounted on the machine and having a member thereon operable upon rotation thereof to move the slide to open position against the urging means and blocking return of said slide by the urging means until said member is returned by the actuation of said means.

7. In an automatic vending machine having a coin-receiving aperture in the exterior surface thereof, a movable slide for opening and closing said aperture; yieldable means normally urging said slide to aperture-closing position; manually operable means mounted on the machine for movement with respect thereto and having a member thereon for moving the slide to open position against the urging means; means for positioning said member with the slide in open position and the member in alignment with and opposing the force of the urging means to block return of said slide by the urging means until said member is manually returned; and means for controlling the said manually operable means.

8. In an automatic vending machine having a coin-receiving aperture in the exterior surface thereof, a slide movable across said aperture on the interior of the machine for opening and closing said aperture; yieldable means normally urging said slide to aperture-closing position; means rotatably mounted on the machine and including a member thereon movable from a normal inoperative position for moving the slide to open position against the urging means; means for stopping said member when the slide is in open position and the member in alignment with and opposing the force of the urging means to block return of said slide by the urging means until said member is returned to normal position; and means for controlling the movement of said member comprising a concealed instrumentality requiring predetermined unobvious complementary manipulation for operation thereof.

9. In an automatic vending machine having a coin-receiving aperture in the exterior surface thereof, a slide on the machine movable across said aperture for opening and closing said aperture; a pivoted operator for said slide; yieldable means normally urging said slide to aperture-closing position; manually operable means rotatably mounted on the machine and having a member thereon engaging said pivoted operator for moving the slide to open position against the urging means; means for arresting movement of said member when the slide is in open position and the member is in alignment with and opposing the force of the urging means to block return of said slide by the urging means until said member is manually returned; and means for controlling the said manually operable means comprising a concealed instrumentality requiring predetermined unobvious complementary manipulation for operation thereof.

RICHARD R. DUNN
